UNITED STATES PATENT OFFICE.

BERT R. BENJAMIN, OF CHICAGO, ILLINOIS, ASSIGNOR TO INTERNATIONAL HARVESTER COMPANY, OF CHICAGO, ILLINOIS, A CORPORATION OF NEW JERSEY.

CORD-HOLDER FOR SELF-BINDERS.

SPECIFICATION forming part of Letters Patent No. 741,296, dated October 13, 1903.

Application filed July 2, 1902. Serial No. 114,092. (No model.)

To all whom it may concern:

Be it known that I, BERT R. BENJAMIN, a citizen of the United States, residing at Chicago, county of Cook, State of Illinois, have invented certain new and useful Improvements in Cord-Holders for Self-Binders; and I do hereby declare the following to be a full, clear, and exact description of the invention, such as will enable others skilled in the art to which it appertains to make and use the same.

The purpose of the present invention is to simplify the construction and improve the operation of the type of holders which consists of a disk revolving in contact with a flat plate, the cord being held between the opposing surfaces of the two parts and the disk being partially rotated during the operation of tying the knot; and the particular object in view is to bring the holding-surfaces up closer to the knotter, so as to economize in the amount of cord required to tie the knot.

The construction is illustrated in the accompanying drawings, wherein—

Figure 1 is a side view of a knotter having a holder constructed in accordance with my invention, the needle appearing in the operation of laying the cord into the holder. Fig. 2 is a view in all respects similar to Fig. 1 except that the knotter is shown as having just completed the knot and the needle as about to recede. Fig. 3 is a sectional plan of the knotter and holder with the parts in the same position as in Fig. 1. Fig. 4 is a similar plan of the same parts with the positions corresponding to those of Fig. 2. Fig. 5 is a plan of the holder-plate detached.

Referring to the views, *a* denotes the frame of the knotter; *b*, the breastplate; *c*, the knotter-bill, and *d* the needle. The knotter-frame 40 is formed with an offset projection *e* on the outer side, which forms a bearing for a hook *f*, having a shank *g* extending upwardly and playing in a slot *h* in the part *i* of the frame. The upper end of the shank is preferably 45 screw-threaded, and a spring *x* is coiled around the rod and reacts between the top of the bearing *e* and a nut *j*, that is adjustable on the shank to vary the tension of the spring. The bearing and the hook are curved, as 50 shown in Figs. 1 and 2, and therefore the hook cannot turn in its bearing. From the point

where the hook emerges from the lower end of the bearing it extends downwardly and is then bent abruptly inward, as shown at *k*, and its extreme end is then preferably upturned, as at *f'*. This hook forms the sole support for the plate *l* of the holder, and the connection between the hook and the plate is made as illustrated in Figs. 1 and 4—that is to say, the outer edge of the plate is provided with a notch *m*, which straddles the straight portion of the hook just below the bearing *e*, and the upturned point *f'* of the hook enters a hole or depression that is provided for it in the under side of the plate at 65 a point diametrically across from the notch and just under that part of the plate where the greatest strain on the cord comes. The plate is thus effectually held from turning and is supported from below, so as to leave 70 its top surface unobstructed for the passage thereover of the disk.

Excepting only in respect of the above-described bearing for the hook *f* the knotter-frame is of the usual construction, and the holder-disk shaft *q* is journaled in the diagonal bearing *n*, so that its pinion stands in the proper relation to the shaft *o* of the cam-wheel *p* to be partially rotated at the appropriate period in the formation of the knot. 80

The holder-disk *x* is rigidly secured to the lower end of the holder-shaft *q* by means of a hub *r*, which extends up around the shaft and bears against the bearing *n*. The shaft *q* preferably extends below the disk and into 85 an eye *s* in the holder-plate, so as to coöperate with the hook *f* in preventing the plate from turning; but there is sufficient clearance between the end of the shaft, the hook *f*, and the plate to allow the latter to have a 90 slight rocking motion to accommodate various sizes and unevenesses of the cord. The lower surface of the disk is flat, and the holder-plate *l* is held up against it solely by the tension of the spring *x*. The plate is here shown 95 as of irregular outline; but its outline is unimportant provided it has a vertical flange *c'* rising from its edge on one side of the vertical transverse plane of the binder, passing through the axis of the knotter, and a knife 100 *a'* on the other side of the plane.

The holder-disk is of the peculiar construc-

tion illustrated in Figs. 2, 3, and 4. It is intended to have, as usual, a half-revolution in the direction of the arrow for every knot formation, and therefore has its construction 5 duplicated at diametrically opposite points of its circumference. Each half of the disk is provided with a notch e' , and just behind the notch there is a hook f^2 , which is raised above the plane of the disk, so that as the 10 disk revolves the hook will catch over the cord, which has been laid in the notch e' by the needle. Behind each hook and on the opposite edge of the notch from the hook the disk is provided with an upstanding lug e^2 , 15 which is straight on its advancing face and extends to the edge of the disk, so as to shear against the knife a' , and has a curved or blunt rear edge to permit the cord to bend around it without danger of scraping or cutting. These 20 lugs are set out from the hub of the disk, leaving a free space between them and the hub. The portions of the disk in rear of the raised hooks f^2 and between these hooks and the cutting-lugs e^2 are flat and below the 25 level of the hook, and when the disk is in position to receive the cord the needle lays it, as represented in Fig. 3, in the free space between the lug e^2 and the hub r diagonally across the notch e' and in advance of and below the succeeding hook f^2 , so that said hook 30 will pass over it, as above referred to. Immediately in front of each lug e^2 the flat surface of the disk is provided with a V-shaped recess v^2 , which permits the needle-strand to 35 be placed as close as possible to the holder-strand, so that the two may be readily seized by the knotter-bill, as shown in Figs. 2 and 4.

Rising from the plate l on the side at which the cord is received in the holder is the flange 40 c' , which is set at an angle to the vertical transverse plane of the knotter above referred to, as best shown in Figs. 3, 4, and 5. Its function is to deflect the cord as it is carried back around the hook f^2 by the needle in its 45 retreat into the position shown at e^5 , where it is in the proper relation to the knotter-bill for the succeeding knot. At the base of the flange the edge of the plate inclines downwardly from the flat holding-surface a^2 , as 50 shown at v , forming a depression which provides clearance-space for the hook f^2 and prevents the binding of the cord at this point as it is carried back. On the opposite side of the vertical transverse plane of the knotter 55 is the knife a' , against which the needle-strand is carried by the lug e^2 and cut at the completion of the knot, and immediately in front of the knife and between it and the holder-shaft on the delivery side of the 60 holder the surface of the plate l is hollowed out or cut away, forming a groove u . Into this groove the holder end of the cord is carried by the disk during the formation of the knot, reducing the holding-surface and allowing the cord to be drawn therefrom by the 65 knotter as it requires slack. After the completion of the knot the cord is released by the

disk, which has advanced sufficiently over the groove to permit the holder-strand to be drawn out and the knot stripped without any 70 resistance from the holder.

It has already been explained that except as to the provision and location of the flange c' , the cutter a' , and the groove u the shape of the plate l , which underlies the disk x^2 , is 75 not an essential feature of the invention. It is desirable, however, to form its upper surface at the outer side of the holder-shaft with a shallow groove or depression t to permit the disk to clear itself of any particles of 80 fiber that may have clung to it and also reduces the friction.

The knotter c shown herein is of that type which makes but one revolution to complete each knot and stands normally with its 85 jaws trending diagonally outward in position to permit of the easy stripping of the knot. As represented in Figs. 3 and 4, the knotter stands a little to one side of the needle-slot w in the breastplate b , and the cord-supporting 90 finger a^3 projects toward the knotter from the far side of the slot.

Fig. 3 indicates the position all the parts are in when the needle lays its end of the cord over the knotter-bill and into the holder. 95 When the cord has been thus laid, the holder-disk starts immediately, and the hook f^2 passes above the needle-strand. The knotter also starts at about the same time, and the lug e^2 , behind which the cord was laid, 100 deflects it over toward the shank of the bill into the position shown in Fig. 4, so as to prevent the cord from escaping the bill and also so as to carry it around to meet the open jaws. While the disk is moving in this 105 way, the needle-strand is free to draw out slack from under the hook f^2 , but just before the lug e^2 reaches the knife a' the surface t^2 at the bottom of the notch e' passes 110 over the edge s^2 , and the needle-strand is immediately gripped between the under side of the disk at the base of the hook and the flat upper surface a^2 of the holder-plate. As will be understood from Fig. 2, the passage of the 115 cord is laid behind it to the point where it 120 shears the cord against the knife causes a considerable bend in the needle-strand before it is gripped, and this bend draws out enough of the needle-strand to pay out slack 125 when this strand is severed and becomes the holder-strand in the formation of the succeeding knot. While this operation has been 130 going on with the needle-strand the cut strand has been held solely by friction between the under side of the part x^2 of the disk and the flat part a^2 of the plate, and as the knotter requires slack at about the time this strand reaches the groove u in the plate the reduced amount of frictional surface at 135 that point permits it to pay out. When the revolution of the holder-disk has progressed to the point indicated in Fig. 4, the needle-strand is cut by the edge of the lug e^2 shear-

ing it against the knife a' and the holder-strand released by the disk passing over the groove. This frees the knot and leaves the needle-strand held by the hook f^2 with its free end pointing toward the knotter, and the further movement of the disk to the point indicated in Fig. 3 carries the end around, as shown at e^4 in that figure, the needle having receded in the meantime and pulled the cord around the edge of the hook f^2 between it and the flange c' into the position e^5 in Fig. 3. This completes the cycle of movements for one knot, and it all occurs during a one-half revolution of the disk and a single revolution of the knotter-bill.

Such being the construction and operation of my holder, it is to be noted that the cord is held entirely by frictional grip between the bottom of the disk and the yielding plate without being belayed around the edge of the hook f^2 , thereby permitting the cord to pass directly from between these surfaces to the knotter and be pulled from between them without resistance when the holding-surface under one of the parts of the cord has passed from off the surface a^2 of the plate over the groove u . It is also to be noted that the arrangement and proportion of these parts provides an extensive holding-surface at the time when there is the greatest strain on the cord and that as soon as the point is reached where slack is required the amount of holding-surface diminishes, so as to permit the end to pay out.

35 Of course the tension of the spring x regulates largely the strength of grip which the parts get on the cord, and as this is adjustable the grip may be regulated as desired to different sizes and conditions of cord.

40 It is also to be noted that all the movements of the cord are toward the knotter and toward the advancing open bill. The cords are thereby prevented from getting away from the knotter and are, moreover, moved in the direction to form the knot with the least possible length of cord.

An important feature of the invention is that the cord is held between flat parallel surfaces, and reliance is had entirely on the 50 tension with which the plate and disk are held together for the frictional grip on the cord. In this way all sharp corners and bends, such as are usually found in the disk type of holders, are dispensed with, and the cord is 55 therefore easier to handle. Moreover, the opposing faces of the disk and plate present an amount of holding-surface that has heretofore not been obtained in any construction of cord-holder of which I am aware, and the 60 liability of the cord scoring or wearing grooves in the holding-surfaces is consequently practically eliminated.

Having thus described my invention, what I claim is—

65 1. In a cord-holder for the knotters of self-binders, the combination of a plate, and a

disk overlying the plate, said disk having a hook to catch over the cord, said hook being shaped to permit the cord to slip over it when the needle recedes so as to hold it entirely by 70 the clamping action between the opposing surfaces of the plate and hook.

2. In a cord-holder for the knotters of self-binders, means for holding the cord consisting of a plate, and a disk overlying the plate, 75 the disk and plate having coöperating frictional holding-surfaces by means of which the cord is held entirely by the clamping action between the plate and disk without being looped around the holder.

80 3. In a cord-holder for the knotters of self-binders, means for holding the cord in a position leading to the knotter without being looped around the holder, said means consisting of a plate, and a rotary disk overlying 85 the plate and coöperating therewith to form the sole means for holding the cord, said disk being notched substantially tangentially to its hub to provide a hook that projects in the general direction of the disk's rotation. 90

4. In a cord-holder for the knotters of self-binders, a stationary knife, and means for holding the cord in a position leading to the knotter without being looped around the holder, said means consisting wholly of a 95 plate, and a rotary disk overlying the plate and coöperating therewith to hold the cord, said disk being notched substantially tangentially to its hub, and having an upstanding lug on the forward side of the notch to deflect the cord against the knife.

5. In a cord-holder for the knotters of self-binders, the combination with the frame of the knotter, of the holder shaft and disk, a holder-plate underlying the disk, and a plate-105 supporting hook mounted in bearings outside of the disk-shaft, said hook engaging the plate at its outer edge and being bent inwardly under the plate and having an upturned end engaging the plate underneath 110 its holding-surface.

6. In a cord-holder for the knotters of self-binders, the combination with the frame of the knotter, of a holder-disk and underlying plate, the holder-shaft extending below the 115 disk and through the center of the plate, a plate-supporting hook mounted in bearings outside of the disk-shaft bearing, said hook engaging a notch in the outer edge of the plate and being bent inwardly under the plate 120 and having an upturned end engaging the under side of the plate at a point near its opposite edge, the shank of the hook carrying an adjustable spring for holding the plate up against the disk with a yielding pressure. 125

In testimony whereof I affix my signature in presence of two witnesses.

BERT R. BENJAMIN.
